Des. No. 251

Prop't. Sam'l Clark
 Commercial parlor stove designs No. 5
 C. Johnson & Co. New York
 Drawing view of damask block
 Patented November 13, 1849. —

Fig. 2

Fig. 1.

Johnson & Hoy, assignees of Samuel Clark, Troy, N.Y.
Letters Patent No. 251. Dated November 13th 1849.
The schedule referred to in these letters patent, and
matrices part of the same.

To all whom it may concern. Be it known that Samuel Clark
of Troy in the County of Rensselaer and State of New
York, have invented or produced a new design of parlor
stove plates, which I call the Commercial parlor No. 5 and
I do hereby declare that the following is a full clear and exact
description of the same, the same being held to the annexed
and drawings making a part of this specification in which
fig. 1 is a view of the front and fig. 2 of the end plate of
the stove.

In the drawings I have represented only part of the arrangement, the remainder being a repetition of and corresponding with that represented on the other parts of the plates as is plain to be seen by reference to the drawings.

What I claim as new and desire to secure by letters patent
is the design and configuration of ornamental stove plates as
herein described and represented in the annexed drawings.
